UNITED STATES PATENT OFFICE

BENJAMIN I. BUCK, OF LINEBORO, MARYLAND

BEAN NIPPING MACHINE

Application filed June 2, 1931. Serial No. 541,655.

My invention relates to improvements in bean nipping machines, and has to do, more particularly, with improvements in the construction of automatic bean nipping machines of the rotary drum type, in which the bean pods enclosed within the drum are thrown, by the rotation of the drum, endwise against the perforated wall thereof, causing the ends of the bean pods to protrude through the perforations in the wall and be subjected to the cutting action of an externally mounted knife to snip said protruding ends.

This application is a continuation, in part, of my copending application, Serial No. 473,827, filed August 8, 1930.

The principal objects of my invention are to provide a bean nipping machine which will snip the ends from bean pods more rapidly and more efficiently than any machines in use, with which I am familiar. That is to say, my object is to provide a machine which will snip the ends from a given quantity of bean pods in a shorter time, and do it more effectively, snipping both ends from a larger percentage of the bean pods treated. It is a further object of my invention to provide a speedy and efficient machine of this character, which can be manufactured at a lower cost than the machines now in general use.

One object of my invention is to provide a bean nipping machine having improved means for upending the bean pods and directing them endwise against the perforated side wall of the drum, and, further, to provide a drum having more perforations per unit of surface, thus rendering the machine more effective.

Another object of my invention is to provide a machine of this character having a gaging device or devices cooperating with the external knife or knives, so that uniform amounts are snipped from the ends of the bean pods, thus rendering the machine more efficient and less wasteful.

Further objects, and objects relating to details and economies of construction and operation, will definitely appear from the description to follow. In one instance, I attain the objects of my invention by the machine de-

scribed in the following specification. My invention is clearly defined and pointed out in the appended claims. A structure constituting a preferred embodiment of my invention is illustrated in the accompanying drawings, forming a part of this specification, in which,—

Figure 1 is a top plan view of a machine embodying my invention;

Fig. 2 is a vertical, sectional view through the machine, taken on the line 2—2 of Fig. 1;

Fig. 3 is a vertical, sectional view through the revoluble drum, taken on the line 3—3 of Fig. 2;

Fig. 4 is a detail, sectional view of the mounting for the upper knife and gage plate, taken on the line 4—4 of Fig. 2;

Fig. 5 is a perspective view of the lower knife supporting bar, knife and gage plate, and

Fig. 6 is a detail sectional view of the upper knife and gage plate, and a portion of the drum, showing a series of bean pods in dotted lines, to illustrate the cooperation of these parts in severing gaged portions from the ends of the bean pods.

In the drawings, the same reference numerals indicate the same parts throughout the several views, and the sectional views are taken looking in the direction of the arrows at the ends of the section lines.

In general, my invention consists in providing a revoluble drum having a perforated side wall and a plurality of longitudinal tumbling rods within the drum, so located as to upend the bean pods within the drum and cause them to be thrown endwise against the perforated wall as the drum revolves, and a knife or knives mounted outside of the drum and so located that the ends of pods protruding through the side wall perforations will be presented to the cutting edge of the knife and snipped off. The perforations should be of such size as to permit the tapered unsnipped ends of ordinary bean pods to protrude therethrough sufficiently to snip off the proper amount. The more perforations provided in the side wall of the drum, the more efficient the machine will be, as the chances are greater of a pod, thrown

against the wall, protruding through a perforation. The tumbling rods perform an important function in directing the pods endwise against the wall, and, being spaced therefrom, I am able to provide closely adjacent perforations throughout substantially the entire wall area, thus rendering my machine very efficient. I prefer to provide a pair of knives, an upper and a lower one, and propose to employ gage plates so located that they engage protruding pod ends and adjust them radially inward through the perforations toward the axis of the drum, as it revolves, so that the amount of protrusion is governed and no more than the desired portion is severed from the end of the pod. This feature also adds considerably to the efficiency of my machine.

Referring to the numbered parts of the drawings, the specific machine here illustrated comprises a revoluble drum formed by the spaced heads 11, keyed on shaft 10, and the cylindrical side wall 12, formed by a sheet of metal fastened to the edges of the head and provided with a multiplicity of perforations 13, located closely adjacent to each other throughout the entire area of the side wall. As shown, these perforations are countersunk or counterbored on the inner side, that is, toward the axis of the drum, the inner end of each perforation being flared, as indicated at 47 (Fig. 6). I have found, however, that this refinement is unnecessary and undesirable, if the wall be thin enough. An opening for charging and discharging is formed in the drum wall, and closed by a removable lid 14, which lid is also perforated so as to constitute, in effect, a portion of the operative surface of the drum. I provide a plurality of tumbling rods 15, which extend longitudinally of the drum parallel to shaft 10. These rods are spaced from the perforated wall being located, in the machine illustrated, inwardly from said wall a distance which is about one-third of the drum radius. These rods are fixed to the drum, as by extending the rods 15 through the heads 11 and clamping them in place by nuts 16 screwed on the rods on opposite sides of the heads. As the drum revolves, due to the cooperative action of the tumbling rods, the pods within the drum will be directed endwise against the side wall and protruded through perforations therein, the ends of the protruding pods being engaged by the gage plates 18 and the pods adjusted in the perforations 13 before meeting the cutting edge of the corresponding knife 17, so that only the proper portion of the pod end is severed by the knife.

The shaft 10 is journaled in bearings 20 carried by the inclined members 21 of a frame or stand, which includes the upper cross bar 22, lower cross bar 23, front and rear legs 25 and 24, and the transverse mem-

bers 26. I have mounted on the stand an electric motor 27, for revolving the drum, which motor is connected, through reduction gearing 28 with a shaft 29, the latter being connected through clutch 30 with shaft 10. The clutch is operated, to connect or disconnect shaft 10 and the driving shaft 29, by lever 31 fulcrumed at 32 and having the actuating rod 33 and handle 34 connected thereto. A hand wheel 35' is fixed on the opposite end of shaft 10, by which the drum may be rotated when the power is off, to bring the opening in the side wall in proper position for charging or discharging.

The angle bars 35, extending longitudinally from one head to the other, frame the charging opening and position the lid 14 closing that opening. The lid frame is formed by the side angle bars 38, and the end angle bars 37 which are curved in conformity to the side wall of the drum, said bars being rigidly connected. To this frame there is fastened a curved sheet of metal, perforated as is the side wall, and constituting, when the lid is in place, a continuation of the side wall. A pin 40 projecting from one of the heads 11 is lodged in a hole in one of the end bars 37 of the lid frame. At a corresponding point in the opposite head 11, there is mounted a spring-pressed bolt 42, which is projected by spring 44, acting on a cross pin 43, into a hole 41 in the adjacent end bar 37 of the lid frame. A handle 45 is provided for retracting bolt 42, and a strap 46 fastened to and spaced from this end of the lid frame forms a handle by which the lid may be removed when bolt 42 is retracted. Bolt 42 and pin 40 cooperate to hold the lid firmly in place while the drum is being rotated.

The upper knife 17 and gage plate 18 are mounted as follows. Hinge members 48 are fastened on the upper cross bar 22 of the stand and hinge members 50 are hinged thereto by pintles 49. Each member 50 has a lug 56 extending at right angles to the body thereof. A knife-supporting bar 51 is adjustably mounted on members 50, said bar having, at its ends, flanges 52 extending at right angles to the bar and seated on members 50. Bolts 53, screwed into members 50, extend through elongated slots 54 in flanges 52, and bolts 57, provided with lock nuts 58 and 59, pass through bar 51 and lugs 56. Thus the bar 51, and the knife 17 and gage plate 18 carried thereby, may be accurately positioned and fixed in the position to which adjusted. The upper knife 17 is a flat bar having the cutting edge 61 and lies against bar 51, and is bolted thereto by bolts 60, with the cutting edge 61 remote from members 50. The knife 17, of course, extends the full length of the drum. The gage plate 18 is formed of a sheet of metal extending the length of the drum and adjustably supported from bar 51 by bolts 62, and nuts screwed thereon and

clamping the gage plate. The latter has an operative gaging surface 63, which is inclined toward and approaches the surface of the drum, as the gaging surface nears the cutting edge of the knife. Figure 6 shows the functioning of the gage plate and it will be observed that, as the drum rotates in the direction of the arrow (Fig. 2), the protruding pods are pushed back through the perforation until, at the instant they meet the knife 17, there is only such protrusion as is required to sever the desired portions from the pod ends. As the pods are brought against the upper knife by the rotating drum, the cutting pressure is exerted in a direction which tends to move the knife toward the inclined members 21 of the stand. The hinge members 50 engage such portions of the stand and prevent such movement of the upper knife. The entire structure carried by the members 50, including bar 51, knife 17 and gage plate 18, may, however, be swung up out of the operative position if desired.

The elements for mounting the lower knife and gage plate are the same as above described, but arranged somewhat differently. Hinge members 48 are fastened to the lower ends of the inclined bars 21 of the stand, and connected by pintles 49 to hinge members 50. The knife-supporting bar 51 is adjustably mounted on members 50, as in the case of the upper knife. The lower knife 17, however, is mounted on bar 51 in the reverse position, with its cutting edge 61 toward the members 50, instead of remote therefrom. The lower gage plate 18 is clamped in position between the knife 17 and bar 51, but, like the upper gage plate, it has a gaging surface 63, which approaches the surface of the drum as it nears the knife. In each case, the cutting edge of the knife is closely adjacent the surface of the drum, so as to snip off the ends of the protruding bean pods to the extent permitted by the gage plates. The lower knife is so mounted that the weight of the parts swings the hinge members 50 against the frame members 21, or blocks secured thereto, which act as stops limiting the movement of the parts in that direction. The structure carried by the lower hinge members 50 is free, however, to swing in the opposite direction, with the result that, if sticks, nails or other hard substances, protrude through the perforations at the bottom of the drum and are carried against the cutting edge of the lower knife, they can swing it back out of the way, thus avoiding injury to the knife. Such foreign materials are more apt to come through at the bottom than at the top of the drum.

In operation a charge of bean pods is placed within the drum through the charge opening, said charge being sufficient to fill the drum about one-quarter full. The lid 14

is then put in place and fastened by the means described. During the charging operation, of course, the clutch 30 is shifted to disconnect shaft 10 from the driving shaft 29 and the drum may be rotated by the hand wheel 35' to bring the charging opening into a convenient position. After the drum has been charged with bean pods and the lid closed and fastened, the clutch is shifted to connect the drum shaft 10 to the driving shaft 29 and the drum is rotated at a suitable speed by the driving mechanism. The rotation of the drum, in cooperation with the tumbling rods 15, throws the bean pods endwise against the perforated wall of the drum with the result that tapered ends of the bean pods project through perforations 13 in the drum wall and as the drum revolves these projecting tapered ends engage the gage plate, as shown in Fig. 6, and are gradually pressed back through the perforations until, at the time the bean pods are presented to the cutting edge of the knife only that portion of the pods which it is desired to remove or snip, protrude. This operation is clearly indicated in Fig. 6. The pod having been snipped drops back into the drum and is again thrown endwise against the drum wall. Snipped ends, however, lacking the pronounced taper, have little or no tendency to extend into and through the perforations so that no more is cut from previously snipped ends of the pods. Unsnipped ends, however, readily slip into the perforations and protrude and are snipped by the cutting knife, 90

or knives. I have found that many of the bean pods are first thrown by the revolution of the drum endwise against the upper part of the drum and when the tapered ends are snipped from such of these pods as protrude through perforations in the upper part of the drum, the pods drop downwardly endwise toward the lower part of the drum and in many instances the opposite ends of such pods fall into and protrude through the perforations at the lower part of the drum with the result that the opposite tapered ends are snipped by the lower cutting knife. The tumbling rods are very important factors in the successive operation of this machine, as they direct the pods endwise against the perforated wall in position such that the tapered ends are apt to protrude through the perforations. These tumbling rods are spaced from the perforated wall and, consequently, the entire surface of the drum wall can be provided with a multiplicity of perforations, thus increasing to a maximum the chance of the end of a bean pod being directed through a perforation in the drum wall. After the drum has been rotated for the desired period, the clutch is shifted to disconnect the power drive, the lid 14 is unfastened and removed and the drum is rotated by the hand wheel 35' to the dumping position to discharge its 100

110

115

120

125

130

contents. The drum may then be rotated by the hand wheel to elevate the charging opening, a fresh charge put in place, the cover replaced and the snipping operation repeated.

- 5 The gage plates are very useful factors in promoting the efficiency of the machine, as they prevent undue protrusion to the cutting edge of the bean pods and so prevent the machine from snipping off too much of 10 the bean, thereby reducing waste to a minimum.

I have secured very good results from the use of a machine such as disclosed in the accompanying drawings in which the drum is 15 about four feet long and about three feet in diameter and in which I use four tumbling rods equidistantly located from each other at about six inches from the periphery of the drum and about a foot from the axis 20 thereof. The perforations in the drum wall are preferably about 9/32 of an inch in diameter at their constricted ends. I have found that, using a machine of such dimensions and revolving the drum at a rate of 25 about fifty revolutions per minute, using a charge of three and one-half bushels of beans which are rotated in the drum for nine minutes, I have been able to snip twenty-one bushels of beans per hour, cutting both ends 30 of ninety-eight per cent of all the beans. This machine, therefore, operates much more efficiently than any other machine with which I am familiar. In addition, it is simple in 35 construction, not likely to get out of repair, and may be constructed at low cost.

I am aware that the machine disclosed herein is capable of considerable variation without departing from the spirit of my invention and, therefore, I claim my invention broadly 40 as indicated by the appended claims.

What I claim is:

1. A machine for trimming the ends of bean pods which comprises a hollow rotary drum within which a charge of bean pods is 45 contained, said drum having its peripheral wall provided with a multiplicity of perforations of such size as to permit the tapered ends of bean pods within said drum to extend endwise into said perforations and protrude 50 beyond the periphery of said drum, means for rotating said drum, means for actively stirring up and tumbling the bean pods within said drum so as to cause large numbers thereof to be directed endwise against said 55 perforate peripheral wall and be projected into and protrude through said perforations, said stirring means comprising a plurality of rods extending across the inner face of said peripheral wall transversely thereof and spaced therefrom a distance such as to permit bean pods to pass through the space between said rods and said wall when said drum is rotated, an external gage member 60 spaced from said peripheral wall, which gage member determines the extent of protrusion of said tapered pod ends through said perforations, and a knife having an edge extending transversely across the outer surface of said peripheral wall in proximity thereto for effecting severance of those portions of the pods which said gage member allows to protrude.

thereto, which edge engages and severs the protruding ends of the bean pods.

2. A machine for trimming the ends of bean pods which comprises a hollow rotary drum within which a charge of bean pods is contained, said drum having its peripheral wall provided with a multiplicity of perforations of such size as to permit the tapered ends of bean pods within said drum to extend endwise into said perforations and protrude 70 beyond the periphery of said drum, means for rotating said drum, means for actively stirring up and tumbling the bean pods within said drum so as to cause large numbers thereof to be directed endwise against said perforate peripheral wall and be projected into and protrude through said perforations, said stirring means comprising a plurality of rods parallel to the axis of said drum, extending from end to end thereof, and spaced from the peripheral wall thereof a distance such as to permit bean pods to pass through the space between said rods and said wall when said drum is rotated, and a knife having an edge extending transversely across the outer face of said peripheral wall in close proximity thereto, which edge engages and severs the protruding ends of the bean pods.

3. A machine for trimming the ends of bean pods which comprises a hollow rotary drum within which the bean pods are contained, said drum having its peripheral wall provided with a multiplicity of perforations of such size as to permit the tapered ends of bean pods within said drum to extend endwise into said perforations and protrude beyond the periphery of said drum, means for rotating said drum, bean pod stirring and tumbling means within said drum operative by rotation of said drum to cause large numbers of unsnipped bean pods to be directed endwise against said peripheral wall and be projected into and protrude through said perforations, said stirring means comprising a plurality of rods extending across the inner face of said peripheral wall transversely thereof and spaced therefrom a distance such as to permit bean pods to pass through the space between said rods and said wall when said drum is rotated, an external gage member 105 spaced from said peripheral wall, which gage member determines the extent of protrusion of said tapered pod ends through said perforations, and a knife having an edge extending transversely across the outer surface of said peripheral wall in proximity thereto for effecting severance of those portions of the pods which said gage member allows to protrude.

4. A machine for trimming the ends of bean pods which comprises a hollow rotary drum within which the bean pods are contained, said drum having its peripheral wall provided with a multiplicity of perforations of such size as to permit the tapered ends of 120

bean pods within said drum to protrude endwise therethrough to a considerable extent, means for rotating said drum, bean pod stirring and tumbling means within said drum operative by rotation of said drum to cause large numbers of unsnipped bean pods to be directed endwise against said peripheral wall and be projected into said perforations and protrude beyond the periphery of said drum, said stirring means comprising a plurality of rods extending across the inner face of said peripheral wall transversely thereof and spaced therefrom a distance such as to permit bean pods to pass through the space between said rods and said wall when said drum is rotated, a knife having an edge extending transversely across the outer surface of said peripheral wall in close proximity thereto for severing the portions of the pods which protrude through said perforations, and gage means for urging said protruding bean pod ends radially inwardly to provide limited and uniform protrusion regardless of variations in thickness of said pods, said gage means comprising a plate disposed transversely across the surface of said peripheral wall in advance of said knife, the leading edge of said plate being spaced from said peripheral wall a distance greater than the portion of said plate which is adjacent the knife edge.

5. A machine for trimming the ends of bean pods which comprises a hollow rotary drum within which the bean pods are contained and are tumbled, said drum having its peripheral wall provided with a multiplicity of outwardly tapering circular perforations which are of such size as to permit tapered ends of bean pods within said drum to protrude endwise to a considerable extent through said perforations, means for rotating said drum and tumbling bean pods into said perforations, a knife having an edge extending transversely across the outer surface of said peripheral wall in close proximity thereto for severing the portions of the pods which protrude through said perforations, and gage means for urging said protruding tapered bean pods radially inwardly to provide limited and uniform protrusion regardless of variations in thickness of said pods and also preventing said tapered ends from being tightly wedged in said perforations, said gage means comprising a plate disposed transversely across the surface of said peripheral wall in advance of said knife, the leading edge of said plate being spaced from said peripheral wall a distance greater than the portion of said plate which is adjacent said knife edge.

6. A machine for trimming the ends of bean pods which comprises a hollow rotary drum within which the bean pods are contained and are tumbled, said drum having its peripheral wall provided with a multiplicity

of perforations of such size as to permit the tapered ends of bean pods within said drum to extend endwise into said perforations and protrude beyond the periphery of said drum, a pair of external knives, one having an edge extending transversely across the external surface of the perforate wall adjacent the lower portion of the drum, the other having an edge extending transversely across the external surface of the perforate wall adjacent the upper portion of the drum, means for actively stirring up and tumbling the bean pods within said drum comprising a plurality of rods extending across the inner face of said peripheral wall transversely thereof and spaced therefrom a distance such as to permit bean pods to pass through the space between said rods and said wall when said drum is rotated, and means for rotating said drum at such speed that bean pods are caused to fall endwise into perforations at a zone in advance of the lower knife and bean pods are projected endwise into perforations at a zone disposed beyond said lower knife and in advance of said upper knife whereby severance of protruding unsevered bean pod ends is effected at two distinct points during such rotation of the drum.

7. A machine for trimming the ends of bean pods which comprises a hollow rotary drum within which the bean pods are contained and are tumbled, said drum having a peripheral wall provided with a multiplicity of perforations of such size as to permit the tapered ends of bean pods within said drum to extend endwise into said perforations and protrude beyond the periphery of said drum, means for rotating said drum and tumbling said bean pods, a pivoted knife so disposed with respect to its pivot point as to normally rest, by reason of its own mass and the force of gravity, with its cutting edge disposed transversely across the outer face of said peripheral wall in close proximity thereto and sever the protruding ends of bean pods, said knife, its center of mass and its pivot point being so positioned with respect to said drum that in the event a foreign object incapable of severance without injury to the knife edge be engaged, said knife will be automatically swung out of its said normal position, and a gage plate carried by said pivoted knife and extending in advance of the knife edge, said gage plate being so disposed with respect to said pivot point as to be able to clear said drum in the event said knife is swung out of normal position by reason of engagement of its edge with such a foreign object.

8. A machine for trimming the ends of bean pods which comprises a hollow rotary drum within which a charge of bean pods is contained and tumbled, said drum having its peripheral wall provided with a multiplicity of perforations of such size as to per-

mit bean pods to enter endwise therein and allow the ends, as well as portions of the tapered bodies of the beans, to extend endwise into said perforations and protrude to a considerable extent beyond the periphery of said drum, means for rotating said drum and tumbling bean pods into said perforations, a knife having its cutting edge extending transversely across the outer surface of said peripheral wall in close proximity thereto for severing the portions of the bean pods which protrude through said perforations, and a device for urging bean pods, disposed in said perforations and protruding therethrough, radially inwardly so as to loosen their contact with the walls of said perforations and preclude their becoming wedged therein, said device comprising a plate disposed across said drum immediately in advance of said knife, which plate has its knife-adjacent portion slightly spaced from said peripheral wall, constituting a gage to limit the extent to which bean pods disposed in said perforations may protrude, and having its remaining portion flaring rearwardly and radially outwardly from said knife-adjacent portion so that its surface first engaged by said protruding bean pod ends is spaced from the peripheral wall of said drum a distance greater than the knife-adjacent portion, and protruding bean pods, in their movement toward said knife, are gradually urged radially inwardly in their perforations.

9. A machine for trimming the ends of bean pods which comprises a hollow rotary drum within which a charge of bean pods is contained and tumbled, said drum having its peripheral wall provided with a multiplicity of outwardly tapering circular perforations of such size as to permit bean pods to enter endwise therein and allow the ends, as well as portions of the tapered bodies of the beans, to extend endwise into said perforations and protrude to a considerable extent beyond the periphery of said drum, means for rotating said drum and tumbling bean pods into said perforations, a knife having its cutting edge extending transversely across the outer surface of said peripheral wall in close proximity thereto for severing the portions of the bean pods which protrude through said perforations, and a device for urging bean pods, disposed in said perforations and protruding therethrough, radially inwardly so as to loosen their contact with the walls of said perforations and preclude their becoming wedged therein, said device comprising a plate disposed across said drum immediately in advance of said knife, which plate has its knife-adjacent portion slightly spaced from said peripheral wall, constituting a gage to limit the extent to which bean pods disposed in said perforations may protrude, and having its remaining portion flaring rearwardly and radially outwardly from said knife-adjacent portion so that its surface first engaged by said protruding bean pod ends is spaced from the peripheral wall of said drum a distance greater than the knife-adjacent portion, and protruding bean pods, in their movement toward said knife, are gradually urged radially inwardly in their perforations.

jacent portion so that its surface first engaged by said protruding bean pod ends is spaced from the peripheral wall of said drum a distance greater than the knife-adjacent portion, and protruding bean pods, in their movement toward said knife, are gradually urged radially inwardly in their perforations.

10. A machine for trimming the ends of bean pods which comprises a hollow rotary drum within which a charge of bean pods is contained and tumbled, said drum having its peripheral wall provided with a multiplicity of circular perforations having their inner portions of countersunk or enlarged conical form to facilitate endwise entrance of bean pods therein, and having their outer portions of non-converging form to reduce tendency of bean pods to become jammed therein, said perforations being of such size as to permit bean pods to enter endwise therein and allow the ends, as well as portions of the tapered bodies of the beans, to extend endwise into said perforations and protrude to a considerable extent beyond the periphery of said drum, means for rotating said drum and tumbling bean pods into said perforations, a knife having its cutting edge extending transversely across the outer surface of said peripheral wall in close proximity thereto for severing the portions of the bean pods which protrude through said perforations, and a device for urging bean pods, disposed in said perforations and protruding therethrough, radially inwardly so as to loosen their contact with the walls of said perforations and preclude their becoming wedged therein, said device comprising a plate disposed across said drum immediately in advance of said knife, which plate has its knife-adjacent portion slightly spaced from said peripheral wall, constituting a gage to limit the extent to which bean pods disposed in said perforations may protrude, and having its remaining portion flaring rearwardly and radially outwardly from said knife-adjacent portion so that its surface first engaged by said protruding bean pod ends is spaced from the peripheral wall of said drum a distance greater than the knife-adjacent portion, and protruding bean pods, in their movement toward said knife, are gradually urged radially inwardly in their perforations.

BENJAMIN I. BUCK.
